UNITED STATES PATENT OFFICE.

RICHARD KHUEN, OF PITTSBURG, PENNSYLVANIA, AND ALBERT REICHMANN, OF CHICAGO, ILLINOIS, ASSIGNEES TO AMERICAN BRIDGE COMPANY, OF PITTSBURG, PENNSYLVANIA, A CORPORATION OF NEW JERSEY.

TURN-TABLE CENTER.

945,723.

Specification of Letters Patent. Patented Jan. 4, 1910.

Application filed April 12, 1907. Serial No. 367,857.

To all whom it may concern:

Be it known that we, RICHARD KHUEN, of Pittsburgh, Allegheny county, Pennsylvania, and ALBERT REICHMANN, of Chicago, Cook county, Illinois, have invented a new and useful Turn-Table Center, of which the following is a full, clear, and exact description, reference being had to the accompanying drawings, forming part of this specification, 10 in which—

Figure 1 is a view showing one half of our improved turn table center in plan view and the other half with the upper plate removed to show the bearing rollers; and Fig. 15 2 is a view of the same partly in side elevation and partly in section.

Our invention has relation to turn table centers, and is designed to provide an improved arrangement of the bearing rollers 20 which carry the load, and also to provide means for the more effective lubrication of the same and for the exclusion of dust.

Our invention consists in the novel construction, arrangement and combination of 25 parts, all substantially as hereinafter described and pointed out in the appended claims.

Referring to the drawings, the numeral 2 designates the base casting of the turn table 30 center, 3 the rotatable top plate or casting, and 4 the cap plate which supports the usual table bridge and table, (not shown.) The base casting 2 is provided in its upper portion with the open annular trough 5, and 35 the rotatable top plate 3 has in its under surface a similar annular trough 6, these two troughs forming a chamber for the series of conical, radially-arranged, bearing rollers 7. These rollers are arranged side by side, and 40 are loosely journaled on the pins 8, said pins being seated in the outer and inner annular rings 9 and 10. These pins are inserted loosely through the outer ring 9, having heads 11 at their outer ends, and their inner 45 ends are formed with reduced threaded portions 12 which engage threaded openings in the inner ring 10.

10' designates a washer, which is interposed between the outer end of each roller 50 and the outer ring.

The pins 8 connect the two rings to keep the rollers in proper relative positions, without the use of connecting ribs, which would take up some of the space available for the

rollers. The rollers 7 are also placed between the upper and lower annular bearing or track plates 13 and 14, which are made separate from the castings 2 and 3, so that they may be of harder metal, and also be readily renewed and replaced if necessary. 60

The space around the rollers forms a lubricant-containing chamber which may be supplied by means of a pipe 15 which extends upwardly through the central portion of the cap 4. The inner wall of this lubricant-containing chamber is sealed by the interfitting of the inner lip 6^a of the trough 6 within the inner lip or wall 5^a of the lower trough 5. The outer lips or walls of these two troughs are made of reduced 70 thickness at the joint, as shown at 16, the upper reduced lip fitting within the lower one, as shown in Fig. 2, and the outer side of the joint or opening between these lips being covered by a dust guard or strip 17. 75 By keeping oil up to line x—x, shown in Fig. 2, complete lubrication of the bearings is assured, and dust and dirt are excluded therefrom.

The cap 4 is provided with the usual rock- 80 ing bearing at 18 on the upper surface of the top plate 3.

The advantages of our invention result from the manner in which the bearing rollers are arranged, so that they can be placed 85 in position, and the pins 8 inserted therethrough, and secured in the inner ring 10 without the use of nuts or other fastening devices; also from the provision of the separate bearing plates for the rollers, and 90 in the construction and arrangement of the lubricant-containing chamber whereby complete lubrication of the rollers is insured.

Various changes may be made in the details of construction and arrangement, without departing from the spirit and scope of our invention. 95

What we claim is:—

1. A turn table center, having a base portion and a rotary top plate or portion, said portions having annular corresponding troughs in their meeting faces, formed by projecting annular flanges from each portion, the flanges of the top portion lying within the flanges on the base, a series of 100 antifriction rollers in the chamber formed by said troughs, a tapered bearing or track plate for the said rollers in each portion, 105

a supporting frame for the rollers, comprising an inner and outer ring and pins projecting through the rollers and the rings, and a turn table bearing cap loosely mounted on the upper surface of the top plate; substantially as described.

2. A turn table center, having a base portion and a rotary top plate or portion, said portions having annular corresponding troughs in their meeting faces, formed by projecting annular flanges from each portion, the flanges of the top portion lying within the flanges on the base, a series of antifriction rollers in the chamber formed by said troughs, a tapered bearing or track

plate for the said rollers in each portion, a supporting frame for the rollers, comprising an inner and outer ring and pins projecting through the rollers and the rings, and an annular dust guard secured to the outer flange of the top plate and extending over the outer flange of the base; substantially as described.

In testimony whereof, we have hereunto set our hands.

RICHARD KHUEN.
ALBERT REICHMANN.
